RESONANT GROUNDING DEVICE FOR
ALTERNATING-CURRENT CIRCUITS

Lawrence H. Harrison, Birmingham, Ala.

Application February 24, 1948, Serial No. 10,551

8 Claims. (Cl. 175—294)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention relates to a resonant grounding device for alternating current circuits.

It frequently occurs in power distribution and utilization systems that a power-carrying conductor accidentally makes contact with the frame of a utilizing machine. It is therefore desirable to provide means whereby in such circumstances the fault current will flow through a low impedance path from the machine frame back to the source. Causing the fault current to flow through a low impedance path not only insures that a large enough fault current will flow to operate the safety device which removes the potential from the faulted line, but also prevents the application of high voltage to the machine frame prior to the operation of the safety device.

In direct current distribution systems one of the power conductors may be kept at ground potential and connected to the frames of the utilizing machinery. When Y-connected secondary transformers are used in an alternating current distribution system, an additional conductor may be installed from the neutral point and connected to the frames of machines to be protected. In a delta-connected distribution system there is no neutral unless one is created by an arrangement of specially added transformers, and it is not advantageous to ground one distribution conductor since this causes an abnormally high potential to exist between the other conductors and ground. In some applications, however, such as a distribution system for coal mines, the delta-connected distribution system has certain advantages and is widely used. Safety grounding in coal mines presents a special problem since it is usually difficult in a coal mine to obtain a low impedance connection to the earth.

One object of this invention is to provide a device to diminish shock hazard in an alternating current system.

A further object of this invention is to provide a device to present a high impedance between distribution power conductors, but a low impedance between the conductors and a fault.

These and other objects will become apparent to one skilled in the art from the following specification, taken in connection with the accompanying drawings, in which:

2

Fig. 1 is a schematic view of a distribution system incorporating the principles of this invention; and

Fig. 2 is a schematic view of the resonant grounding device provided by this invention.

Fig. 3 is a partial schematic view of the resonant grounding device used with a current relay.

Fig. 1 shows a cross section of the earth's surface 10 in which there is a coal mine shaft 11 and gallery 12. A delta-connected transformer bank 14 supplies 3-phase alternating current through power conductors 16, 17 and 18.

Conductors 16, 17 and 18 descend through shaft 11 into gallery 12 where they are connected to the electrical components of utilizing machines 25—25, such as a drill or blower. Each machine 25 has a metal frame which is insulated from the electrical component. Each machine 25 is connected to conductors 16, 17 and 18 through safety devices 20, 21 and 22, respectively. Safety devices 20, 21 and 22 may consist of fuses, circuit breakers, or any device operating to open the circuit a predetermined time after an abnormal current flows therethrough. In coal mining it is usual for a number of electrically driven mechanisms to be used in one vicinity, as shown in Fig. 1.

Relatively adjacent to machines 25—25 there is connected to conductors 16, 17 and 18 a grounding device 28. Grounding device 28, shown in detail in Fig. 2, comprises induction coils 29, 30 and 31, one end of each coil being connected to a common neutral point 32. Between each pair of the other ends of coils 29, 30 and 31 are connected one of the capacitors 33, 34 and 35. Conductor 36 connects the neutral point 32 with the frames of machines 25. One grounding device 28 will provide a grounding medium for any number of machines.

Coils 29, 30 and 31 and capacitors 33, 34 and 35 are so selected that any two coils, such as 29 and 30, connected in series and this series circuit connected in parallel with capacitor 34 across any two of the power conductors such as 16 and 17 will provide a resonant parallel circuit at the frequency of the distribution system. It will thus be seen that a high impedance is provided through the grounding device between any pair of distribution conductors 16, 17 and 18. However, the circuit from the frame through the neutral point 32 and any two of coils 29, 30 and 31 to any two of the distribution conductors 16, 17 and 18 presents a non-resonant and relatively low impedance path for the return of fault cur-

rent to the power system. The inductance coils 29, 30 and 31 of device 28 are preferably wound about a magnetic core, as indicated in Fig. 2, to reduce the size of the device.

In operation, when there is no fault occurring in the distribution system, no appreciable current will flow through the grounding device because of the high impedance offered by the parallel resonant paths therein. However, if through a breakdown in the insulation of the machine 25, one of the power conductors 16, 17 or 18 accidentally comes in contact with a machine frame 26, a low impedance path will be provided from the faulted conductor through the frame of motor 25, connecting wire 36, and grounding device 28 back to the distribution system source 14.

Since a low impedance is thus presented to the fault current, the potential of the faulted conductor will immediately drop and, therefore, no high voltage can be applied to the machine frame by reason of the fault. Also, because of the low impedance path provided, a large fault current will flow and the safety devices 20, 21 or 22 will quickly operate to remove the potential from the faulted conductor.

The neutral point 32 of the resonant grounding device 28 may be grounded by making a good connection with the earth, as shown at connection 37 in Fig. 2. Alternatively, the neutral point 32 may be connected to the frames of the utilizing machinery, as shown in Fig. 1, without such an earth connection. In practice, however, such a device would probably be enclosed in a metal case, indicated at 38 in Fig. 2, which would usually be in contact with the earth. Therefore, a positive connection to the ground would be desirable, and this would normally involve connecting the neutral point 32 to earth.

Fig. 3 shows a part of a modified circuit in which a relay 40 is used to trip circuit breaker contacts 46, 47 and 48, connecting power conductors 16, 17 and 18 with the motor 25'. Grounding device 28 is connected to power conductors 16, 17 and 18 as in Figs. 1 and 3. Conductor 33 from the neutral point of the grounding device 28 is connected in series with the operating coil of relay 40 and the frame of motor 25'. Contacts 42 and 43, which are closed when relay 40 is energized, are connected in series with trip coil 44 of the circuit breaker which includes contacts 46, 47 and 48. Trip coil 44 and contacts 42-43 are connected across one flow of the power conductors such as 16 and 17.

In Fig. 3, when a fault occurs and the current through the frame of motor 25' and conductor 36 exceeds a predetermined value, relay 40 will operate to close contacts 42-43, which are normally open. Operation of relay 40 energizes trip coil 44, causing the opening of circuit breaker contacts 46, 47 and 48 to remove the operating voltage from machine 25'. It will be obvious that a normally closed relay could be substituted for normally open relay 40, in which case contacts 42-43 would be connected in series with the low voltage release of the circuit breaker, including contacts 46, 47 and 48.

With the resonant grounding system set forth above, the power taken from the system by reason of the grounding device will be negligible due to the high impedance presented by the parallel resonant circuit between phases. Because of this it will be possible to locate such a device near the working faces in the mine, and thus obviate the installation of a fourth wire from the power source to the frames of each machine. Since the

machines tend to be grouped, one grounding device may be provided for each group. Such a grounding device should be materially less expensive than the transformers necessary to establish a separate neutral position on a delta power system and will have the further advantage of providing a lower impedance to the flow of fault current.

It will be understood that the details of the invention as set forth above are by way of example only, and that many modifications and changes will occur to those skilled in the art within the scope of the appended claims.

What is claimed is:

1. In a delta-connected alternating current distribution system having a plurality of power conductors, a utilizing machine having a metal frame and an electrical component connected to said conductors, a grounding device separate from said utilizing machine having a neutral point connected to said frame, said neutral point being connected through an inductance to each of said conductors, each pair of ends of said inductances adjacent said conductors being connected through a capacitor, the inductances and capacitors being so selected that at the frequency of the distribution system a parallel resonant path is presented between any pair of conductors.

2. In a three-phase delta-connected alternating current distribution system having three power conductors and operating at a predetermined frequency, a utilizing machine having a metal frame and an electrical component connected to at least two of said conductors, a grounding device separate from said utilizing machine having a neutral point connected to said frame, said neutral point being connected through an inductance to each of said conductors, each pair of ends of said inductances adjacent said conductors being connected through a capacitor, the inductances and capacitors being so selected that at the frequency of the distribution system a parallel resonant path is presented between any pair of power conductors.

3. The combination of claim 2 in which said neutral point is connected to earth.

4. The combination of claim 2 in which there is a safety device connected between said electrical component and said conductors, said safety device operating to disconnect said electrical component from said conductors when the current flowing from said conductors to said electrical component exceeds a predetermined value.

5. In a three-phase delta-connected alternating current distribution system having three power conductors and operating at a predetermined frequency, a utilizing machine having a metal frame and an electrical component connected to at least two of said conductors, a grounding device having a neutral point connected to said frame, said neutral point being connected through an inductance to each of said conductors, each pair of ends of said inductances adjacent said conductors being connected through a capacitor, the inductances and capacitors being so selected that at the frequency of the distribution system a parallel resonant path is presented between any pair of power conductors, a safety device connected between said electrical component and said conductors, said safety device operating to disconnect said electrical component from said conductors when the current flowing between said neutral point and said frame exceeds a predetermined value.

6. In a three-phase delta-connected alternat-

ing current distribution system having three power conductors and operating at a predetermined frequency, a utilizing machine having a metal frame and an electrical component connected to at least two of said conductors, a grounding device having a neutral point connected to said frame, said neutral point being connected through an inductance to each of said conductors, each pair of ends of said inductances adjacent said conductors being connected through a capacitor, the inductances and capacitors being so selected that at the frequency of the distribution system a parallel resonant path is presented between any pair of power conductors, a safety device connected between said electrical component and said conductors, said safety device including a circuit breaker, said circuit breaker having a trip coil operating to disconnect said electrical component from said conductors when the current flowing between said neutral point and said frame exceeds a predetermined value.

7. The combination of claim 6 in which the electrical component of the utilizing machine is electrically insulated from the metal frame thereof.

8. In a three-phase delta-connected alternating current distribution system having three power conductors and operating at a predetermined frequency, a utilizing machine having a

10
15

metal frame and an electrical component connected to at least two of said conductors, a grounding device separate from said utilizing machine having a neutral point connected to said frame, said neutral point being connected through an inductance to each of said conductors, each pair of ends of said inductances adjacent said conductors being connected through a capacitor, the inductances and capacitors being so selected that at the frequency of the distribution system a parallel resonant path is presented between any pair of power conductors, the electrical component of said utilizing machine being electrically insulated from the metal frame thereof.
